PILE RAISING STRUCTURE

Leon W. Atwater, Williamston, Mich.

Application February 17, 1940, Serial No. 319,400

30 Claims. (Cl. 61—73)

The present invention relates to a device for raising piles which have been embedded in the ground and more particularly to a device wherein the raising is assisted by a series of sharp, intermittent blows.

Frequently, it is desirable to raise piles which have been driven into the ground, either for the purpose of salvaging or for removing them because their presence is undesirable. This problem arises frequently with respect to interlocking sheet piling. Heretofore, so far as is known, such piling has been withdrawn by means of a steady pull. The present invention contemplates the provision of apparatus which is connected to piling and subjected to a steady pull and at the same time is subjected to a series of blows by an internally disposed hammer. The hammer is actuated to give a series of blows by a stepped, or equivalent, cocking and tripping structure which is moved through a single cycle to impart a plurality of strokes to the hammer.

An object of the present invention is to provide a pile raising structure arranged for connection to a pile or the like to be raised and for imparting, by hammering, a plurality of sharp pulling impulses in rapid succession.

Another object of the invention is to provide a pile raising structure having a cocking and tripping mechanism which by moving through a single stroke imparts a plurality of strokes to a hammer.

A further object of the invention is to provide a hammering structure having a hammer, a cocking and tripping finger and a stepped member for successively actuating the cocking and tripping member a plurality of times in rapid succession.

A still further object of the invention is to provide a hammering structure having means for readily pre-loading a hammer actuating spring in combination with means for moving the hammer to impart a plurality of blows in rapid succession.

A still further object of the invention is to provide a hammering device of the character described adaptable to pile driving as well as pile raising.

These and other objects relating to the construction, operation and combination of the parts will be apparent from the following specification when taken with the accompanying drawings in which:

Fig. 1 is a vertical section of the invention showing one form thereof with the hammer against the anvil.

Fig. 2 is a partial vertical section of the form of the invention as shown in Fig. 1 but in a different position.

Fig. 3 is a perspective view of a portion of the structure included in the form of the invention disclosed in Figs. 1 and 2.

Fig. 4 is a section on the line IV—IV of Fig. 1, Fig. 5 is a section on the line V—V of Fig. 1, Fig. 6 is a section on the line VI—VI of Fig. 1, Fig. 7 is a perspective view of the finger and its tail piece for cocking and tripping the hammer,

Fig. 8 is a perspective view of the portion of the ladder member and its guide shown separated from the hammer to which it is welded,

10 Fig. 9 is a partial vertical section of another form of the invention,

Fig. 10 is a section on the line X—X of Fig. 9, Fig. 11 is a view taken from the line XI—XI of Fig. 9,

15 Fig. 12 is a perspective, disclosing a detail of the stepped member employed in the construction of Fig. 9,

Fig. 13 is a partial vertical section of another form of the invention,

20 Fig. 14 is a section taken on the line XIV—XIV of Fig. 13,

Fig. 15 is a side elevation disclosing the construction according to the present invention adapted to driving piles,

25 Fig. 16 is a front elevation of the construction disclosed in Fig. 15, and,

Fig. 17 is a section on the line XVII—XVII of Fig. 16.

Referring to the drawings, the reference character 1 indicates a tubular body in which is slidably disposed a tubular hammer 2. Adjacent one end of the body 1 is an anvil 3 preferably fabricated separately as shown in Fig. 3, and welded in its position shown in Figs. 1 and 2. The normal position of the hammer 2 is against the anvil 3, it being held there by a spring 4. The lower end of the spring 4 bears against a shoulder 5 at the inner end of a tubular sleeve 6, having flanges 7 in alignment with flanges 8 on the lower end of the body 1. The flanges 7 and 8 are clamped together by bolts 9 and nuts 10.

As will be observed from Fig. 1, the bolts 9 are particularly long. The reason for the length is to permit the positioning of the sleeves 6, as shown in dotted outline, and at the same time, permit the bolts 9 to extend through the flanges 7 and 8 so that by taking up on the nuts 10, the sleeves 6 may be moved inwardly with respect to the body 1 to load the spring 4. The spring 4 should be substantially loaded. As an example of the load that should be applied, it has been found that with a hammer 2 weighing 400 pounds, the spring 4 should be loaded so as to urge the hammer 2 upwardly against the anvil 3 with a force of 400 pounds.

In Fig. 1, the body 1 is shown connected to a pile 15 to be raised from the ground 16. The connection is made by a universal link consisting of a pair of bars 17 connected directly to the pile 15 by a pin 18 and to a member 19 by a pin 20.

The member 19 is connected by means of a pin 21 to the body 1 and sleeve 6, the pin 21 extending through bosses 22 in the sleeve 6 and bosses 23 on the body 1.

A pulling cable 24 is connected to the body 1 by means of a pin 25 extending between bars 26 bridging the opposite end of the body 1 from the flanges 8 and welded to the opposite side of the anvil 3 from the hammer 2. The pulling cable 24 is connected to a derrick, or the like, and maintained under tension thereby to draw the pile 15 from the ground. In order to assist the pulling action of the cable 24, the hammer 2 is made to hammer against the anvil 3.

The hammering action by the hammer 2 is obtained by cocking the hammer 2 against the spring 4 and tripping it, by a finger 27 pivoted by means of a pin 28 between a pair of plates 29 projecting downwardly from the anvil 3. The finger 27 is urged about its pivotal axis by a spiral spring 30 shown particularly in Fig. 3, into engagement with a shoulder 31 on the hammer 2 formed by providing an axially extending slot 32 therein. A hand hole 33 shown in Fig. 6 is provided in the body 1 opposite the pin 28 to permit removal of the pin 28 and the spring 30 and thus the finger 27 when the hammer 2 has been removed from the body 1.

On the opposite side of the pin 28 from the finger 27 is an integral rigidly connected tail piece 36, normally in the path of movement of a ladder-like member 37, having steps 38. Suitably welded to the inside surface of the hammer 2 opposite the ladder-like member 36 is a bar 39 for the purpose of providing a guide for the longitudinal movement of the ladder-like member 37. The steps 38 are set slightly inwardly from the side of the ladder-like member 37, adjacent the wall of the hammer 2 so as to provide a channel for receiving the bar 39, as shown particularly in Figs. 2 and 8. The ladder-like member 37 has connected to it a cable 40 which is connected to a suitable pulling member, such as an auxiliary drum, for instance, on the derrick employed to pull on the cable 24.

Opposing the action of the cable 40 on the ladder member 37 is a spring 41, connected at one end at 42 to the ladder member 37 and at the other end to a pin 43 secured to a boss 44 in turn secured by welding to the interior surface of the sleeve 6. As shown particularly in Fig. 1, the lower end of the ladder member 37 is provided with a bridging bar 45 which in the absence of tension in the cable 40 bears against the boss 44 under the action of the spring 41.

In the position shown in Fig. 1 the hammer 2 is urged against the anvil 3 by the spring 4 and there is sufficient tension on the cable 40 to draw the ladder member 37 upwardly against the action of the spring 41, to bring the top step 38 into the contact with the tail piece 36 on the finger 27 and to raise the bridging bar 45 from the boss 44. Continued upward movement of the ladder member 37 under the action of the cable 40 results in rotating the finger 27 about the axis of its pin 28 to force the hammer 2 downwardly away from the anvil 3, as is shown in Fig. 2. At the point of relative movement between the top step 38 and the tail piece 36, as shown in Fig. 2, when the counter-clockwise rotational movement of the tail piece 36 has moved it laterally to the edge of the top step 38, the stop step 38 slips from beneath the tail piece 36. At that instant the spring 4 drives the hammer 2 upwardly

against the anvil 3. The inertia of the finger 27 will cause it to leave the shoulder 31. However, immediately the spiral spring 30 serves to rotate the finger 27 back into its starting position into engagement with the shoulder 31 and places the tail piece 36 in position to catch the next to the top step 38.

In order to insure that the tail piece 36 will catch the next to the top step 38 and also to employ the sudden upward movement of the released ladder member 37 as an auxiliary driving force against the hammer 2, there is provided a swinging arm 46 in the form of a pair of bars connected together at one end by a projecting dog 47 and pivoted by a pin 48 on either side of a projecting bracket 49 welded to the inner side of the hammer 2 adjacent the lower end thereof, as shown in Fig. 1. A curved leaf spring 50 pivoted between the bars of the arm 46 about a pin 51 and biased toward one wall of the hammer 2 by a pin 52, resiliently urges the arm 46 toward the ladder member 37 to carry the dog 47 into the space between two steps 38. The dog 47 and the arm 46 are so positioned as to have a step 33 on the upwardly moving ladder member 37 contact with the dog 47, at the instant at which a step 38 slips past the tail piece 36 to trip the hammer 2. To accomplish this result, the distance that a step 38, in engagement with the tail piece 36 moves upwardly, from the position shown in Fig. 1 at the start of the upward movement of the tail piece 36, to the position at which that step 38 slips off the tail piece 36, plus the distance that hammer 2 is moved downwardly under the action of the finger 27, should equal the distance between adjacent steps 38. Due to the resiliency which is inherently in the cable 40 and the sudden upward movement of the ladder member 37 due to the release of the step 38 from beneath the tail piece 36, the ladder member 37 through the connection provided by a step 38 and the dog 47 will assist the spring 4 in driving the hammer 2 upwardly against the anvil 3. Also, the fact that the dog 47 is positioned between the two steps 38 will insure that the ladder member 37 will not move upwardly a greater distance than required to permit the tail piece 36 to be disposed over the next lower step 38.

In order to move the dog 47 from lateral engagement with the step 38 with which it is engaged immediately following the tripping of the hammer 2, there is welded between the plates 29, between which the finger 27 is pivoted, a cam 53 for engaging with the dog 47 slightly before the hammer 2 reaches the anvil 3. Thus the upward movement of the dog 47 will cause it to be cammed laterally by the cam 53 and out of engagement with the step 38 with which it has been engaged. In other words, the dog 47 and its supporting lever 46 together with the steps 38 act as an escapement.

The number of steps 38 in the ladder member 37 is optional, although there should be a sufficient number to provide a reasonable number of blows by the hammer 2 for each cycle of operation of the hammer member 37. It will be observed that the bridging member 45 across the lower end of the ladder member 37 is directly beneath the lower end of the hammer 2 so that the member 45 serves as a stop to limit the upward movement of the ladder member 37. To obtain this result, the bridging member 45 should be sufficiently spaced from the lowest step 38 to engage the lower end of the hammer 2 at sub-

stantially the same time that the lowest step 38 engages dog 47.

In Figs. 9, 10, 11 and 12, another form of the invention is shown. The body 1, hammer 2 and anvil 3 are the same as the form shown in Fig. 1. Also, the hammer 2 is provided with a loading spring 4 and associated construction, not shown, but like that as disclosed in Fig. 1. Likewise, the hammer 2 is provided with a shoulder 31 at the base of a slot 32 extending downwardly from the upper end thereof, against which a finger 58 bears. The finger 58 is like the finger 27 of Fig. 1 and is supported from a pair of spaced plates 59 welded to the underside of the anvil 3, by means of a pin 60, to which it is keyed. Like the finger 27, the finger 58 is provided with a spiral spring, not shown, but like the one shown in Fig. 3, for the purpose of continually urging it against the shoulder 31.

The essential difference between the form of the invention disclosed in Figs. 9 through 12 and the form disclosed in Fig. 1 is in the ladder-like or stepped member for actuating the finger. As disclosed in Fig. 9, the stepped member consists of a bar 61 having disposed therein in longitudinally spaced relation, a plurality of steps 62, disclosed more in detail in Fig. 12. The steps 62 are slideable laterally in the bar 61, their lateral sliding movement being limited by pins 63, one-half of each being disposed in grooves in the bar 61 and the other half of each being disposed in laterally extending slots 64 in the steps 62. The steps are arranged for successive engagement upon lifting of the bar 61 with a tail piece 65 on the finger 58.

Welded to the hammer 2 and associated with the bar 61 is a block 66 having cut therein a channel 67 for the purpose of receiving in succession the rear ends 68 of the steps 62. Projecting downwardly from the anvil 3 is a cam 69 having a tapered end 70 for engaging behind the steps 62 in the channel 67 to cam them outwardly thereof. To permit removal of the pin 60 when the hammer 2 has been removed from the body 1, so that the finger 58 may be removed, a hand hole 71 in the body 1, shown in Fig. 11, is provided.

The structure of Fig. 9 is connected for operation in a similar manner to the structure of Fig. 1. In the structure of Fig. 9, a cable 24 from a derrick is connected to the pin 25 at the upper end of the body 1, and at the lower end thereof there is a connection, not shown, to the piling as disclosed in Fig. 1. The cable 40 is connected to a pin 75, bridging a slot 76, cut in the upper end of the bar 61. A tension is placed on the cable 24 and the cable 40 is drawn upwardly to move the steps 62 successively past the tail piece 65. As the steps 62 move upwardly, each one engages with the tail piece 65 to rotate the finger 58 about the axis of the pin 60 to move the hammer 2 downwardly. At the instant a step 62 moving upwardly arrives opposite the slot 67, it moves to the right as shown in Fig. 9 to free the tail piece 65. The movement of the step 62 to the right is the result of the camming action by the tail piece 65. This action permits the spring 4, not shown in Fig. 9, to drive the hammer 2 upwardly against the anvil 3. As each step 62 moves upwardly past the finger 65, it comes into contact with the inclined surface 70 of the cam 69 which moves it into the dotted line position shown in the drawings. In the left-hand position shown, above the tail piece 65, the steps 62

are in position to pass upwardly through the opening 77 in the anvil 3.

It will be understood that the bar 61 is provided with a stop, not shown, similar in operative effect to the stop 45 disclosed in Fig. 1 for limiting the upward and downward movement of the bar 61. When the bar 61 has reached its upper limit and is being moved downwardly under the action of the spring 41, not shown in Fig. 9, the steps 62 move downwardly through the opening 77 in the anvil 3. Should the vibration have moved any of the steps 62 to the right, as shown in Fig. 1 when they are above the anvil 3, there is provided a camming surface 78 in the anvil 3 for camming the steps 62 to the left. Also, to prevent jamming in the event of an accidental moving of the steps 62 to the right after they have passed beneath the anvil 3, the lower edge 79 of the slot 67 is inclined to cam the steps 62 to the left again. It is to be understood in positioning the lower surface 79 of the slot 67 that the position of the surface 79 determines the limit of the cocking and the point of the tripping of the hammer 2.

Another form of the invention is disclosed in Figs. 13 and 14. In this form of the invention, the stepped member is replaced by a rack 80 driving a pinion 81, pivoted on a pin 82 between two plates 83, depending from the anvil 3. Between the plates 83 and to each side of the pinion 81 are pivoted about pins 85 a pair of dogs 84. Each dog 84 is provided with a seat portion 86 for loosely bearing against the pin 82, as shown in Fig. 13.

The hammer 2 is provided with a shoulder 87 against which the dogs 84 are adopted to bear in pairs. As the pinion 81 is rotated by the rack 80, two dogs 84 at a time move the hammer 2 downwardly with respect to the anvil 3 until the dogs 84 slip off the shoulder 87, thereby releasing the hammer 2 and permitting it to be driven upwardly against the anvil 3 by the spring 4, not shown. It will be understood that the rack 80 is provided with a stop, not shown, similar to the stop 45 disclosed in Fig. 1 for limiting the upward and downward movement thereof under the action of a cable 40 and spring 41, respectively. When the rack 80 has reached the top of its movement and is moved downwardly under the action of the spring 41, the dogs 84 pivot about their pins 85 to move the seat portions 86 thereof away from the pin 82 to permit the dogs 84 to move upwardly past the inside wall of the hammer 2 adjacent the seat 87, as the pinion 81 is rotated under the action of the downwardly moving rack 80. When upward movement of the rack 80 is started again, gravity serves to position the dogs 84 so that they will engage with the seat 87 on the hammer 2 to cock and trip the hammer 2 as described.

In order to remove the pinion 81 after the construction has been originally assembled by welding the anvil 3 to the body 1, in the position shown, a hand hole 88, provided in the side of the body 1 for permitting access to the pin 83 so that it may be removed when the hammer 2 has been removed from the body 1.

In Figs. 15, 16 and 17, the invention is shown used in an inverted position to drive piles rather than to raise them. Referring particularly to Figs. 15 and 16, the body 1 is secured for vertical movement to a support 90 by a sliding connection 91. A supporting cable 92 is connected to what would normally be the lower side of the body 1. The cable 92 passes over a pulley 93 on a der-

derrick 94. Suitably secured to the outside of the body 1 as by welding are a pair of downwardly projecting bars 95, having welded between them a bridging plate 96. The bars 95 are bifurcated at the bottom to provide a slot 97 in each for fitting over the top side of the piling 98, which in Figs. 15 and 16, is shown as inter-locking sheet piling. The bridging plate 96 is in alignment with the inner ends of the slots 97 and rests on the top of the sheet piling 93 to distribute the intermittent driving force exerted through the bars 95. The elongated longitudinally moving cocking and tripping member which in the construction of Fig. 1 is the ladder-like member 37, in the construction of Fig. 9, is the bar 84, and in the construction of Fig. 13, is the rack 80, is connected to a bar 99, projected downwardly as shown in Figs. 15 and 16. At the lower end of the bar 99 is an eye 100, to which is connected a cable 101, which passes beneath a pulley 102 at the bottom of the support 90, and over a pulley 103 at the top of the support 90, through some pulling structure as an auxiliary drum on the derrick 94, such as employed to draw the cable 40 of the structures disclosed in Figs. 1 through 14. It is preferred that the shaft supporting the pulley 103 be the same shaft of the derrick 94 that supports the pulley 93. It will be obvious from an understanding of the structures disclosed in Figs. 1 through 14, that as the cable 101 is drawn over the pulleys 102 and 103 to draw downwardly on the bar 99, the hammer in the body 1 of Figs. 15 and 16 will transmit its hammering force through the body 1 and bars 95 to the piling 98.

In order to prevent lateral deflection of the above ground portion of the piling 98 as it is being driven downwardly, the bridging plate 96 has an extension 104 in which there is an opening 105 surrounding the supporting member 99. Thus as the piling 98 is driven downwardly, lateral deflection will be prevented by the guiding action provided by the opening 105 about the supporting member 99. During the driving of the piling 98, it will be understood that the cable 92 should be slackened off as the piling 98 is driven into the ground, as the only function of the cable 92 is to raise the body 1 vertically with respect to its support 90. In order to maintain the support 90 against lifting when a tension is placed on the cable 101, the upper end of the support 90 is connected to the shaft of the pulleys 93 and 103 by a U-clamp 106 or some suitable equivalent, so that the upward thrust against the pulley 102, exerted by the cable 101, is resisted by the derrick 94.

Due to the extreme degree of vibration to which the apparatus, according to the present invention, is subjected, it is important that all joints and connections wherever possible be welded in order to prevent accidental separation. While there is disclosed one form of arrangement by which the apparatus, according to the present invention, may be adapted to pile driving or hammering, it is to be understood that it is not considered that this is the only form possible. Furthermore, the invention is not limited solely to use in driving or raising piles, but may have other applications.

Having thus described my invention, what I desire to secure by Letters Patent and claim is:

1. In a hammering device, a hammer, resilient means for driving said hammer, means for moving said hammer back against said resilient means and tripping it a plurality of times in

succession, a cyclically operating longitudinally stepped member for actuating said second named means to move back and trip said hammer a plurality of times during a single cycle of movement of said stepped member, tension means for operatively moving said stepped member in one direction, and resilient means for returning said stepped member to its initial position.

2. In a hammering device, a hammer, resilient means for driving said hammer, means for moving said hammer back against said resilient means and tripping it a plurality of times in succession, and a cyclically operating elongated member having steps for actuating said second named means to move back and trip said hammer a plurality of times during a single cycle of movement of said stepped member, and an escapement connected to said hammer for controlling the movement of said steps during the movement of said stepped member.

3. A device of the character described for hammering a body comprising a spring driven hammer, mechanism including a longitudinally movable stepped member for periodically cocking and tripping said hammer for hammering the body, tension means for operatively moving said stepped member in one direction, and resilient means for returning said stepped member to its initial position.

4. A device of the character described for hammering a body comprising a spring driven hammer, a pivoted finger for cocking and tripping said hammer, a cyclically longitudinally movable stepped member for actuating said finger to periodically cock and trip said hammer a plurality of times during each cycle of movement to hammer said body, and an escapement connected to said hammer for controlling the movement of said member during the movement of said stepped member to cock and trip said hammer.

5. In a hammering device, a hammer, an anvil for connection to the object to be hammered, hammer actuating means, longitudinally movable stepped means for periodically cocking and tripping said hammer through said hammer actuating means, whereby said hammer is moved away from said anvil and driven by said hammer actuating means against said anvil, tension means for operatively moving said stepped means in one direction, and resilient means for returning said stepped means for its initial position.

6. In a hammering device, a hammer, an anvil for connection to the object to be hammered, a spring for driving said hammer, a bracket fixed with respect to said anvil, a finger pivoted to said bracket, an operative connection between said finger and said hammer, stepped means for actuating said finger to periodically cock and trip said hammer to hammer said anvil, tension means for operatively moving said stepped means in one direction, and resilient means for returning said stepped means to its initial position.

7. A device of the character described comprising a tubular body, a tubular hammer slidably disposed within said body, an anvil in said body adapted to be hammered by said hammer, a shoulder within said body, a spring between said hammer and said shoulder for urging said hammer toward said anvil, a bracket connected to said anvil projecting into said tubular hammer, and means for cocking and tripping said hammer whereby said hammer is moved away from said anvil against the action of said spring and released to permit said spring to drive said hammer against said anvil, said cocking and tripping

means including a finger pivoted to a part of said bracket within said hammer.

8. A device of the character described comprising a tubular body, a tubular hammer slidably disposed within said body, an anvil in said body adapted to be hammered by said hammer, a shoulder in said body, a spring between one end of said hammer and said shoulder for urging said hammer toward said anvil, a bracket within and fixed with respect to said body, said bracket extending into said hammer, a finger pivoted to said bracket on a part thereof within said hammer, said finger having an operative connection with said hammer, and means for actuating said finger for periodically cocking and tripping said hammer to hammer said anvil.

9. A device of the character described comprising a tubular body, a tubular hammer slidably disposed within said body, an anvil in said body adapted to be hammered by said hammer, a shoulder in said body, a spring between one end of said hammer and said shoulder for urging said hammer toward said anvil, a bracket within and fixed with respect to said body, a finger pivoted to said bracket, a shoulder on said hammer, means for urging one end of said finger against said last-named shoulder, stepped moving means for actuating said finger to periodically cock and trip said hammer to hammer said body, tension means for operatively moving said stepped means in one direction, and resilient means for returning said stepped means to its initial position.

10. A device of the character described comprising a tubular body, a tubular hammer slidably disposed within said body, an anvil in said body adapted to be hammered by said hammer, a shoulder in said body, a spring between one end of said hammer and said shoulder for urging said hammer toward said anvil, a bracket within and fixed with respect to said body, a finger pivoted to said bracket, a shoulder on said hammer, means for urging one end of said finger against said last-named shoulder, a longitudinally movable stepped member operatively associated with said finger, guiding means on said hammer for said stepped member, and means to longitudinally move said stepped member to actuate said finger to periodically cock and trip said hammer to hammer said anvil.

11. A device of the character described comprising a tubular body, a tubular hammer within said body, an anvil in said body, adapted to be hammered by said hammer, a finger pivoted with respect to said body, an operative connection between said finger and said hammer, stepped means, means to exert a force on said stepped means to move the same to cause the said stepped means to actuate said finger to periodically cock and trip said hammer to hammer said anvil, a member pivoted to said hammer, and a tooth connected to said member, said member being movable to project said tooth into the path of movement of said stepped means as said hammer is cocked, whereby upon a tripping of said hammer the force exerted on said stepped means to move the same is transmitted to said hammer through one of the steps of said stepped means and said member.

12. In a hammering device, a hammer, an anvil for connection to the object to be hammered, a spring for driving said hammer, stepped moving means having an operative connection with said hammer for cocking and tripping said hammer, whereby said hammer is moved away from said anvil against the action of said spring and

released to permit said spring to drive said hammer against said anvil, and an escapement connected to said hammer for controlling the movement of said stepped moving means.

13. In combination with means to exert a continuous pull on a body, an anvil connected to said body, a hammer, a spring for driving said hammer against said anvil, cyclically operable stepped moving means having an operative connection with said hammer to cock and trip said hammer a plurality of times per cycle in rapid succession to assist said pulling means, a connection between said anvil and said moving means, and pulling means operating in the same direction as said first named means to actuate said stepped moving means.

14. In combination with means to exert a continuous pull on a body, an anvil connected to said body, a connection between said means and said anvil, a hammer, a spring for urging said hammer toward said anvil, stepped moving means having an operative connection with said hammer to cock and trip said hammer a plurality of times in rapid succession to assist said pulling means, elastic pulling means operating in the same direction as said first named means to actuate said stepped moving means, and an escapement connected to said hammer for controlling the movement of said cocking and tripping means, whereby the pulling force exerted by said elastic pulling means is periodically transferred to said hammer through said escapement.

15. In a hammering device, a hammer, an anvil for connection to the body to be hammered, a spring for driving said hammer, and a longitudinally movable elongated member having a plurality of laterally movable steps having an operative connection with said hammer for cocking and tripping said hammer, whereby said hammer is moved successively away from said anvil against the action of said spring and released to permit said spring to drive said hammer against said anvil.

16. In a hammering device, a hammer, an anvil for connection to the body to be hammered, a spring for driving said hammer, a finger pivoted with respect to said anvil, and a longitudinally movable elongated member having a plurality of laterally movable steps for acting on said finger in succession to cause the same to cock and trip said hammer a plurality of times in succession, whereby said hammer is moved successively away from said anvil against the action of said spring and released to permit said spring to drive said hammer against said anvil.

17. A hammering device comprising a tubular body, a tubular hammer slidably disposed within said body, an anvil in said body adapted to be hammered by said hammer, resilient means for driving said hammer against said anvil, a finger within said body and hammer pivoted between its ends with respect to said body, a shoulder on said hammer, one end of said finger bearing against said shoulder, and an elongated longitudinally movable member having a plurality of laterally movable steps movable with respect to said body, said steps being movable laterally into operative relation to the other end of said finger for successively acting on the same during longitudinal movement of said member to cause said finger to cock said hammer and being movable successively laterally in the opposite direction to release said end of said finger to trip said hammer to hammer said anvil.

18. In a hammering device, a hammer, an an-

vit for connection to the body to be hammered, a spring for driving said hammer, a finger pivoted with respect to said anvil, a member having a laterally movable step for moving said finger to cock said hammer, means to move said member longitudinally to move said step to move said finger in cocking direction, and a camming surface on said finger to cam said step laterally out of operative relation therewith to trip said hammer.

19. In a hammering device, a hammer, an anvil for connection to the body to be hammered, a spring for driving said hammer, a pinion pivoted with respect to said anvil, a rack reciprocably movable with respect to said anvil, in operative relation with said pinion, and means movable by said pinion, upon a single reciprocation of said rack, to cock and trip said hammer a plurality of times in succession, whereby said hammer is moved successively away from said anvil against the action of said spring and released to permit said spring to drive said hammer against said anvil.

20. In a pile raising mechanism, a hammer unit, suspension means for the hammer unit, means for connecting a pile to said unit, a reciprocable loadable hammer in said unit, means for transferring blows from said hammer to said unit, a cyclically operable reciprocable member, and means for providing and releasing a plurality of loading connections between said hammer and said member for imparting a plurality of strokes to said hammer during each cycle of operation of said reciprocable member, tension means for operatively moving said member in one direction, and resilient means for returning said member to its initial position.

21. A pile driver or the like comprising an anvil, a cable for supporting said pile driver, a longitudinal guide therefor, a hammer, a spring urging said hammer toward said anvil, means to cock and trip said hammer a plurality of times in succession, and a cable for actuating said means, said second cable acting in the direction of hammering of said hammer.

22. A pile raising mechanism comprising a casing, a connection on said casing for a cable for supporting said casing and for exerting a steady upward pull therein, an anvil in said casing, a reciprocable hammer in said casing, a spring for urging said hammer against said anvil, an upwardly movable member, a connection between said member and said hammer for urging said hammer downwardly to compress said spring when said member is moved upwardly, a connection between said hammer and said member for unitary movement of said hammer and member following a downward movement of said hammer, and a connection upon said member for a cable.

23. A pile raising mechanism comprising a cable supported hammer unit, a second cable actuated loading and firing structure for said hammer movable relatively to said hammer unit during the loading of the hammer, and means for connecting said structure and hammer unit together for unitary movement when said hammer unit is fired.

24. A device of the character described comprising a hammer, resilient means for driving said hammer, a cocking finger for said hammer, cyclically operable stepped means movable past said finger to actuate said finger to cock and trip said hammer a plurality of times for each

cycle of operation thereof, and tension means acting in the direction of hammering to move said stepped means, and being arranged with respect to said hammer to employ the resistance to cocking to supplement the action of the hammer.

25. A device of the character described comprising a hammer, resilient means for driving said hammer, a cocking finger for said hammer, stepped means movable past said finger to actuate said finger to cock and trip said hammer, an escapement operatively associated with said stepped means to control the operation of said stepped means, and tension means acting in the direction of hammering to move said stepped means, and being arranged with respect to said hammer to employ the resistance to cocking to supplement the action of the hammer.

26. A device of the character described comprising a hammer, an anvil for connection to the object to be hammered, resilient means for driving said hammer, cyclically operable means to move said hammer against the action of said resilient means to compress the same, and to suddenly release said hammer to drive the same against said anvil a plurality of times during each cycle of operation of said means, and an operative connection between said hammer moving means and said anvil to direct the resistance to compressing said resilient means against said anvil in hammering direction to supplement the action of said hammer.

27. A device of the character described comprising a hammer, an anvil for connection to the object to be hammered, resilient means for driving said hammer, a cocking finger for said hammer, stepped means movable past said finger to actuate said finger to cock and trip said hammer, an escapement supported by said hammer to control the operation of said stepped means, means on said anvil for moving said escapement to render the same inoperative temporarily to permit movement of said stepped means, and means to operatively move said stepped means.

28. A device of the character described comprising a hammer, resilient means for driving said hammer, a cocking finger for said hammer, longitudinally movable means to actuate said finger to cock and trip said hammer, and tension means acting in the direction of hammering to move said longitudinally movable means to employ the resistance to cocking to supplement the action of the hammer.

29. A device of the character described for handling a body comprising a spring driven hammer, mechanism including a longitudinally movable stepped member for periodically cocking and tripping said hammer for hammering the body, and an escapement associated with said stepped member for controlling the movement of said stepped member during the movement of said stepped member which periodically cocks and trips said hammer.

30. A device of the character described comprising a hammer, resilient means for driving said hammer, a cocking finger for said hammer, cyclically operable stepped means movable past said finger to actuate said finger to cock and trip said hammer a plurality of times for each cycle of operation thereof, and means to move said stepped means.
